Richard Olivera

ATTORNEY

UNITED STATES PATENT OFFICE.

AUGUSTUS BURTON, OF WADLEY, GEORGIA.

PACKAGE-TIE.

1,283,658.

Specification of Letters Patent.

Patented Nov. 5, 1918.

Application filed May 21, 1917. Serial No. 170,017.

To all whom it may concern:

Be it known that I, AUGUSTUS BURTON, a citizen of the United States, residing at Wadley, in the county of Jefferson and State 5 of Georgia, have invented certain new and useful Improvements in Package-Ties, of which the following is a specification.

This invention relates to new and useful improvements in package ties and the principal object of the invention is to provide 10 a device of this nature which will hold the twine in place on the package against slipping and one which will hold the ends of the twine without tying the same.

15 A further object of the invention is to provide a device of this character with means for receiving the twine each time it is passed around the package, and other means for engaging and holding the end of the twine after it has been passed around the package.

20 Another object of the invention is to provide a device of this character, which is simple and durable in construction, reliable and efficient in operation and one which can 25 be manufactured and placed upon the market at a minimum cost.

The invention also consists in certain other 30 features of construction and in the combination and arrangement of the several parts, to be hereinafter fully described, illustrated in the accompanying drawings, and specifically pointed out in the appended claims.

35 In describing my invention in detail, reference will be had to the accompanying drawings, wherein like characters denote like or corresponding parts throughout the several views, and in which:

Figure 1 is perspective view of the device in use on the package.

40 Fig. 2 is a plan view of the device.

Fig. 3 is an edge view thereof.

In these figures, 1 indicates the base plate 45 of the tie, preferably made of circular form and having round edges so as to not cut the package, and this plate is formed with an opening 2 adjacent one edge, which is provided with an eyelet 3 to prevent cutting the twine. 4 indicates a disk of dish shape secured to the plate 1 by means of a rivet 50 or the like passing through its center whereby the space between the said plate and the disk gradually increases toward the outer edge of the disk. 5 represents a stud secured to the plate and having an enlarged

head 6. 7 indicates an oblong plate having 55 a pointed end and secured to the plate 1 by the rivet 8. The plate 7 gradually decreases in thickness toward the pointed end so as to provide a space between the said plate 7 and the plate 1 at the free end 60 thereof.

The plate 7 is arranged opposite the disk 4 and the stud 5 is arranged opposite the opening 2 and these members are located close to the periphery of the plate 1. 65

The twine is passed through the opening 2 and secured therein, and then the twine is passed around the package and brought back to the tie where it is passed a quarter way around the stud 5 and then passed 70 around the package again, at the side thereof, and is then passed a quarter way around the stud 5, though in an opposite direction from the first quarter turn, and the twine is then passed partly or all the 75 way around the disk 4 and is finally passed under the plate 7. Thus the end of the twine is firmly held by the plate 7 and the disk 4 and the loops around the package are firmly held in place by the stud 5. 80

It is thought from the foregoing that the advantages and novel features of my invention will be readily apparent.

I desire it to be understood that I may make slight changes in the construction and 85 in the combination and arrangement of the several parts, provided that such changes fall within the scope of the appended claims.

I claim as my invention:

1. A package tie comprising a disk shaped 90 base plate having an opening therein, a stud, a frictional dish shaped disk, and a frictional plate all of which are arranged around the edge of the base plate.

2. A package tie comprising a base plate 95 having an opening therein, a stud oppositely arranged of said opening, a frictional disk secured to the base plate at a point equidistant from the opening and the stud, and a frictional plate secured to the base plate 100 opposite the frictional disk.

3. A package tie comprising a disk shaped base plate having an opening therein adjacent the edge of the disk, a stud diametrically arranged from the opening, a 105 dish shaped disk secured adjacent the edge of the base plate and at a point equi-distant from said opening and said stud, and a fric-

tional plate secured adjacent the edge of the base plate and diametrically of the frictional disk.

4. A package tie comprising a disk having a hole therein to receive one end of the twine, a stud on the plate diametrically arranged of said opening over which the twine is looped after being passed around the package, a dish shaped disk on the plate to receive the twine after it leaves the stud, and a frictional plate secured to the base plate

and arranged diametrically of the dish shaped disk to receive the twine after it leaves the disk.

In testimony whereof I affix my signature 15 in presence of two witnesses.

AUGUSTUS BURTON.
